US0D1010128S

(12) **United States Design Patent** (10) Patent No.: **US D1,010,128 S**
(45) Date of Patent: ** Jan. 2, 2024

(54) **EAR CANDLE**

(71) Applicant: **Zitao Cen**, Guangdong (CN)
(72) Inventor: **Zitao Cen**, Guangdong (CN)
(**) Term: **15 Years**
(21) Appl. No.: **29/844,949**
(22) Filed: **Jul. 1, 2022**
(51) LOC (14) Cl. **24-02**
(52) U.S. Cl. **USPC D24/151; D26/6**
(58) **Field of Classification Search**
USPC D24/119, 133, 146, 147, 151; D26/6
CPC .. A61F 11/006; A61F 11/00; A61F 2240/001;

(57) **CLAIM**

The ornamental design for an ear candle, as shown and described.

DESCRIPTION

FIG. 1 is a perspective view of the ear candle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of a portion indicated with numeric 8 in FIG. 6; and,

FIG. 9 is an enlarged view of a portion indicated with numeric 9 in FIG. 7.

The uneven broken lines in FIGS. 6 through 9 are for the purpose of showing the bounds of the enlarged FIGS. 8 and 9 views and form no part of the claimed design.

1 Claim, 9 Drawing Sheets
